ASHTON GEORGE STEVENSON, OF CHICAGO, ILLINOIS, ASSIGNOR TO CHICAGO LINOTABLER COMPANY, OF CHICAGO, ILLINOIS, A CORPORATION OF ILLINOIS.

PRINTING-RULE AND SYSTEM OF APPLYING SAME TO PRINTING-FORMS.

974,718.

Specification of Letters Patent.

Patented Nov. 1, 1910.

Application filed July 5, 1910. Serial No. 570,333.

To all whom it may concern:

Be it known that I, ASHTON GEORGE STEVENSON, a citizen of the United States, and a resident of Chicago, Cook county, 5 Illinois, have invented certain new, useful, and Improved Printing-Rules and System of Applying Same to Printing-Forms, of which the following is a full, clear, and exact description, such as will enable others skilled in the art to which it appertains to make and use the same.

My invention relates to the art of molding and composing type by machinery and has special reference to the co-called ruling of type forms by the application of separate rules thereto, and particularly to type forms of the kind produced by linotype and other type casting machines. As will appear hereinafter, my invention is also applicable to 20 the ruling of forms composed of ordinary hand set type.

The primary object of my invention is to provide a ruling system comprising special rules and attaching means, and which shall 25 reconcile the use of such rules to the dimensions of the type and type slugs produced by type matrices of the shape and depth commonly employed.

My invention consists in the combination 30 of a type form which presents or has a substantially level top surface and type rising therefrom, with a rule resting on said top surface and a plurality of projections upon and rising above said top surface and serving 35 to hold said rule thereon.

More specifically defined, my invention consists in a rule which rises to the height of the type faces, in operative combination with a plurality of parts which are integral 40 with the type form body and engage said rule above said top surface and below the plane of said type faces.

The invention will be more readily understood by reference to the accompanying 45 drawings, forming part of this specification and in which;

Figure 1 is a perspective view of a ruled type form embodying my invention; Fig. 2 is a perspective view of one of the linotype 50 slugs shown in Fig. 1, the dotted lines of Fig. 2 being indicative of the fact that my invention is adaptable to lines made up of separate type, as contrasted with a linotype or logotype slug. Fig. 3 is a vertical section on the plane of the line X—X of Fig. 1,

clearly showing the position of the rules on the top surface of the type form and the projections on said surface by which the rules are held, some of said projections being shown as they appear when either intentionally or accidentally bent or battered against the rules; Fig. 4 is a similar sectional view showing the projections as they appear when deliberately and uniformly bent or pressed against the rules to increase their holding or locking effect thereon; Figs. 5, 6, 7 and 8 are enlarged cross-sections showing some of the various shapes in which my novel rules are made.

In the drawings 2, 2, represent a plurality 70 of so-called lino-type slugs the upper edges of which ordinarily conform to a single plane 3 and constitute the top surface of the type form. The type, 4, are molded upon and rise from this surface being formed at 75 the same time as the body of the slug. Strictly speaking, each type comprises a shoulder 4' and a type proper thereon, and the plane of the surface, 3, constitutes the base of the shoulder. I arrange my rules, 80 5, directly upon the surface, 3, between the columns of type thereon. These rules which rest on the surface, 3, are substantially the same height as the type. It being necessary 85 to secure the rules to the type form I provide special metallic fastenings for the purpose, such fastenings being characterized by the fact that they project upwardly from the surface, 3, and engage the rules at points above said surface. As indicated in the 90 drawings these metallic fastenings may be of several kinds or shapes. They are formed directly on the top surfaces of respective type bodies or slugs by the same method which is employed in forming or casting the 95 type. As clearly indicated in Figs. 5 to 8 inclusive the rules which I prefer to use are triangular or substantially triangular in cross-section, each thereof presenting a broad base to the top of the type form and 100 having a narrow upper or ruling edge, preferably disposed midway above the broad base. The height of the type upon most linotype slugs ranges from thirty to fifty thousandths of an inch and the rules substantially correspond to this dimension, from which it will be seen that the terms "broad" and "narrow" are relative, the differences being barely perceptible to the 105 eye, and the drawings herein are greatly 110

enlarged and indicate maximum differences of dimension between the bases and the printing edges of the rule.

I do not herein claim my novel rule, aside from its association with the holding means. The rule is so claimed in my co-pending application Serial Number 507,217 filed July 12, 1909.

For fastening, locking or anchoring the rule upon the form, I employ projections which are integral with the type bodies or slugs and are formed in matrices similar to those used in forming the type. I frequently use these integral locking projections in conjunction with the separable anchoring plates 7 or 7' (see Fig. 1) arranged between the slugs and engaging the rules, but quite as often, I dispense with such independent fastenings and utilize only the integral projections. The plates 7 and 7' are fully disclosed and claimed in my said application Serial Number 507,217 and are not claimed herein, except in combination with the other fastenings. The integral projections, 6, are in most cases arranged in pairs on the slugs, there being two for each rule and the rule resting upon the top surface, 3, between such lugs; but a single lug or projection will serve the purpose when the rule is laid directly against a type shoulder, in which case the type takes the place of one lug. It is apparent that by arranging a rule between alternately positioned lugs on the several slugs, I may avoid the necessity for complete pairs at each point, but this is rarely desired. These lugs, 6, may be of various lengths and cross sectional forms suited to the easy draft of the metal from the matrices. Their only important dimension is height, this being always less than the height of the type so that the projections shall not be imprinted upon the paper in the press. The position of the lugs or projections, upon the slugs determines the position with respect thereto of the rule and it is obvious that by molding or positioning the projections upon the form in a predetermined arrangement the rules may be held in any desired position upon the top surface of the form. When linotype slugs provided with such lugs and rules as described, are locked in the chase they will usually be shifted slightly with respect to one another and this movement, together with the unavoidable inaccuracy of alinement of the anchoring projections, insures the retention of the rules. This action, however, need not be and is rarely relied upon to permanently fasten the rules but instead such locking effect is added to by the accidental and also the intentional battering or bending of the projections against the rules, as indicated in the drawings. The metal from which type slugs are cast is relatively soft and I have experienced no difficulty in battering or

bending the lugs upon or against the rule, as well shown in the drawings.

As indicated by the dotted lines in Fig. 2, both kinds of projections here described may be used upon separate spaces or high quads in connection with ordinary single or mono-type. My novel rules and rule holding projections, lugs, or integral anchor parts, as herein suggested, may be made in many different forms, and I desire it to be understood that my invention is not limited or confined to the specific forms, shapes, and arrangements of parts herein shown and described.

Having thus described my invention, I claim as new and desire to secure by Letters Patent:

1. A type form which has a substantially level top surface and type molded upon and rising therefrom, in combination with a rule resting on said top surface and a plurality of projections integral with said top surface of the form, said projections rising above said top surface at opposite sides of said rule and engaging said rule to hold the same on said surface, substantially as described.

2. A type form which has a substantially level top surface and type molded upon and rising therefrom, in combination with a rule resting on said form and rising to the height of said type and a plurality of projections rising from, integral with said top surface, of less height than said type and engaging opposite sides of said rule to hold the same on said surface, substantially as described.

3. A type form having two rule engaging projections on and integral with its top surface and a rule of substantially triangular cross section secured thereon by and between said projections, substantially as described.

4. A type form having a substantially level top surface and type molded upon and rising therefrom, in combination with a rule having a printing edge at the top and a broad bottom resting on said surface and integral projections on said surface engaging opposite sides of said rule below the plane of the type faces and holding the rule on said surface, substantially as described.

5. A type form having a substantially level top surface and type rising therefrom, in combination with a rule laid on said surface and rising to the height of said type, integral projections upon said surface and serving to secure said rule thereto and one or more auxiliary rule fastenings each comprising a plate arranged between the lines of type perpendicularly to the rule and interlocked therewith, substantially as described.

6. The improvement herein described comprising a type slug having a space thereon, of less height than a type and composed of relatively soft, bendable metal and having a pair of rule holding lugs or projections in-

tegral with and upstanding on said space, at least one of said lugs being bendable to grip and hold a rule resting on said space and between said lugs.

5 7. A type form composed of slugs of relatively soft bendable metal, said slugs presenting a top surface and type molded upon and rising therefrom and the top surfaces of said slugs being provided with integral 10 upstanding bendable projections of less than type height, collectively disposed to receive a rule between them and adapted to retain such rule on said surface.

8. The herein described improvements in 15 ruled type forms comprising a type form having a substantially level top surface and type molded upon and rising therefrom, in combination with a rule laid upon said surface and said form surface having integral 20 upstanding lugs or projections bent or compressed against the sides of said rule and locking the rule in place upon said surface.

9. The herein described improvements in 25 ruled type forms comprising a type form having a substantially level top surface and type molded upon and rising therefrom, in combination with a substantially triangular rule laid upon said surface and said form

surface having integral lugs or projections bent or compressed against said rule and 30 locking the same in place upon said surface.

10. A type form having a substantially level top surface bearing several rows of raised type and also having two rows of integral upstanding bendable projections, said 35 rows of projections extending at right angles to the rows of type and positioned to grip and hold a rule between them.

11. A type form having a substantially level top and rows of type rising above and 40 integral with respective portions of said surface, in combination with a rule resting on said surface and rising to the same height as said type, bendable projections upstanding from said surface and integral with said 45 form, said projections being disposed in rows on opposite sides of said rule and fastening the same on said surface.

In testimony whereof, I have hereunto set my hand, this 27th day of June, 1910, in the 50 presence of two subscribing witnesses.

ASHTON GEORGE STEVENSON.
